(No Model.)

L. J. ATWOOD.
ARGAND LAMP.

No. 436,093.

Patented Sept. 9, 1890.

UNITED STATES PATENT OFFICE.

LEWIS J. ATWOOD, OF WATERBURY, CONNECTICUT, ASSIGNOR TO THE PLUME & ATWOOD MANUFACTURING COMPANY, OF SAME PLACE.

ARGAND LAMP.

SPECIFICATION forming part of Letters Patent No. 436,693, dated September 9, 1890.

Application filed April 4, 1889. Serial No. 305,941. (No model.)

To all whom it may concern:

Be it known that I, LEWIS J. ATWOOD, of Waterbury, in the county of New Haven and State of Connecticut, have invented an Improvement in Argand Lamps, of which the following is a specification.

Argand lamps have heretofore been made use of in which the reservoir is supported by a cylinder of metal with an ornamental porcelain exterior and a base or foot, the parts being held together by screws, and the air for the interior of the flame passing in through the ornamental base, and in other instances an ornamental supporting-base has been made use of and the atmosphere has been admitted into an annular space around the wick-tube, extending down to the bottom of the central air-tube and within the fountain or reservoir.

The object of my present invention is to make an Argand lamp and its reservoir in such a manner as to be adapted to set within and be supported by an ornamental vitrified vase, such vase being closed at the bottom, so that any oil that may drip from the reservoir of the lamp or from the central air-tube may be received into such vitreous vase and effectually kept from the table or other support for the lamp, and hence this vase can be made use of for other purposes when not required for the lamp; and in order to regulate more effectually the air which passes into the central air-tube the supply is preferably taken through the opening between the top edge of the vase and the metal of the reservoir, and I also construct the central air-tube in such a manner that any oil passing off from the wick will be returned in the reservoir, and I provide a double foraminous skirt to the deflector above the air-tube for the purpose of more effectually preventing the lamp being influenced by external drafts of air.

In the drawings, Figure 1 is a vertical section of my improved lamp. Fig. 2 is a detached view of the locking device for uniting the wick-tube housing to the top of the reservoir. Fig. 3 is a detached plan view of the same. Fig. 4 is a horizontal section of the air-tube at the line $x-x$ of Fig. 1; and Fig. 5 is a partial horizontal section at the line $y-y$, Fig. 1.

The reservoir or fount A is of metal, having a projecting and preferably downwardly curved flange B, adapted to set over the top of the vase C. This vase is of suitable size 55 and more or less ornamental in its character, and in order to raise the fountain, so that the atmosphere may pass above the top of the vase and between the same and the projecting and downwardly-curved flange B, I make 60 use of the hangers D, in the form of sheet-metal springs or lugs riveted or soldered to the exterior of the reservoir and bent outwardly within the projecting flange B, so as to rest upon the top edge of the vase C and support 65 the fountain and leave a proper width of opening for the admission of air, as indicated by the arrows, Fig. 1. If desired, openings may be made in the vase C of any suitable character—such as indicated by the holes at 3—or the 70 top of the vase may be corrugated or scalloped, as indicated by dotted lines in Fig. 1. When the hangers D are made as springs, as shown in Fig. 1, they can yield to inequalities in the internal diameter of the top of the 75 vase.

There is a central opening through the bottom of the reservoir A, and the central air-tube E is fastened to the bottom of this reservoir, and in order to strengthen the fastening 80 and more effectually hold the central air-tube in its correct position I place around the lower part of this central air-tube a conical brace 4, having its upper end soldered or brazed firmly to the outside of the air-tube and its 85 lower edge resting upon the upper surface of the reservoir-bottom, and this central air-tube is passed through the opening in the bottom of the reservoir and is soldered firmly into its place. This conical base stiffens the 90 air-tube, and it also serves to deflect outwardly the lower end of the cylindrical wick, such wick being split at its lower end and of sufficient length to reach to the bottom of the reservoir when the cylindrical portion of the 95 wick has been considerably burned or consumed. The bottom of the reservoir is corrugated radially, so that air may pass to the central air-tube when the reservoir may have been lifted out of the vase and set upon a 100 table or other support.

The top end of the air-tube E is contracted to

form a cylinder having a support 6 for the deflector or flame-spreader, and there is a short tube 7 slipped upon the outside of the air-tube E and firmly fastened thereto at the offset 8 between the smaller and larger parts of the air-tube, so that this short tube 7 forms the upper end of the tube around which the wick F is placed, and there is an oil-receptacle 9 between the upper end of the air-tube and the short tube 7, so that any oil flowing over the top of the tube 7 from the wick may pass into the receptacle 9 and return into the reservoir through a hole at 10, and through the lower part of the tube 7. By this construction a very strong and reliable connection is made between the air-tube E and a short tube 7 within the wick F, and the upper end of the air-tube being cylindrical and at the same height as the top of the wick-tube K, or nearly so, the oil-receptacle 9 is deep and cylindrical, and there is no risk of overflow from capillary action, and such receptacle 9 is also adapted to receive within it the lower end of the cylindrical skirt 11. This air-tube E forms at its upper end a support to the foraminous skirt 11 of the flame spreader or deflector G. This foraminous skirt and flame-spreader have heretofore been made use of by me in Argand lamp-burners; but in lamps having a large cylindrical wick I have found difficulty in regulating the amount of air passing inside the flame so perfectly as to prevent the flame being influenced by external currents of air. To avoid this difficulty, I make use of an internal foraminous skirt 12, hanging from the flame-spreader G and passing down inside of the central air-tube E. I find that this internal foraminous skirt does not materially obstruct the air passing up the central air-tube E to the flame; but it serves to check any sudden action of the air induced by external drafts, and hence the flame is much more steady, and smoking is avoided. There may be a second internal foraminous hanging skirt, as indicated by dotted lines, if so desired.

There is an ornamental top H to the reservoir A, the central opening in which is considerably larger than the air-tube E, in order that there may be sufficient room for the insertion or removal of the wick F, the wick-raising cylinder I, and the wick-tube K outside of such cylinder I, and there is around the wick-tube K a collar or housing L, the lower edge of which is a flanged cylinder having at one or two places inwardly-projecting teats 13, adapted to pass down into the vertical grooves 14 in the central cylindrical portion of the ornamental top H of the reservoir, and in this central portion there are horizontal depressions or slots 15, so that the collar or housing L and the parts connected therewith are firmly held upon the top of the reservoir by giving to the collar and wick-tube

a partial rotary movement to bring the teats 15 into such slots 14, and the parts can be disconnected by the reverse motion.

The wick-raising pinion is represented at M, and a movable foraminous air-distributer N surrounds the wick-tube K, and at O are the chimney-holding springs, and a second air-distributer S, which is conical, surrounds the wick-tube near the upper end and within the base of the chimney.

I claim as my invention—

1. The combination, with a supporting-vase, of an Argand lamp-reservoir having a central air-tube opening through the bottom of the reservoir and an outwardly-projecting flange at the top end of the vase, and hangers resting upon the top edge of the vase and between the same and the flange of the reservoir, substantially as set forth. 75

2. The combination, with the Argand lamp-reservoir having a central air-tube opening through the bottom and outwardly-projecting supports around such reservoir, of a vase having a closed bottom and on which the vase stands, the base being higher and larger in internal diameter than the reservoir to leave a space between the vase and reservoir for the passage of air to the central air-tube of the burner, substantially as specified. 85 90

3. The combination, with the Argand lamp-reservoir A, of the central air-tube E, securely fastened to the bottom of the reservoir at the central opening therein and the conical brace surrounding the air-tube and fastened thereto and resting upon the upper surface of the reservoir-bottom, substantially as set forth. 95 100

4. In an Argand lamp, the central air-tube, the upper end of which is on a level, or nearly so, with the top of the exterior wick-tube and cylindrical and of a smaller diameter than the lower part of such air-tube, there being an offset between the larger and smaller parts of the air-tube, in combination with the short tube 7, corresponding in diameter with the lower portion of the air-tube and fastened at its lower end at the offset, there being an opening to allow oil to pass back to the wick from the annular oil-receptacle, substantially as specified. 105 110

5. The combination, with the central air-tube E in an Argand lamp, of the flame-spreader G and two hanging foraminous skirts, one within the other and connected with such flame-spreader, substantially as set forth. 115

6. The combination, with the vase and the Argand lamp-reservoir, of springs fastened to the reservoir and forming hangers for the reservoir, substantially as set forth. 120

Signed by me this 1st day of April, 1889.

L. J. ATWOOD.
